VARIABLE CONDENSER

Arthur Schmidt, Berlin, Germany, assignor to
 Telefunken Gesellschaft für Drahtlose Tele-
 graphie m. b. H., Berlin, Germany

Application October 30, 1933, Serial No. 695,773
 In Germany October 31, 1932

2 Claims. (Cl. 175—41.5)

An object of the present invention is to provide a variable condenser which may be easily and cheaply manufactured, preferably from a ceramic material.

5 A further object of the invention is to provide a condenser of ceramic material in which both rotor and stator elements are formed of such material and carry condenser plates formed of thin layers of metal sprayed or galvanized thereon.

10 A still further object is to provide a condenser structure in which the stator and rotor conducting elements consist of concentrically arranged substantially semi-cylindrical surfaces. Other objects of the invention will become apparent to 15 those skilled in the art as the description thereof proceeds.

The novel features which I believe to be characteristic of the invention are set forth in particularity in the appended claims, the invention 20 itself, however, as to both its organization and method of operation will best be understood by reference to the following description taken in connection with the accompanying drawings in which:

25 Fig. 1 is a cross section taken through the axis of the rotor;

Fig. 1a is a side view of the condenser from the right of Fig. 1 with one end broken off;

Fig. 2 is an axial section through the rotor 30 only;

Fig. 3 is an axial cross section of the stator only;

Fig. 3a is a side view from the left of the stator with one end broken off; and,

35 Fig. 4 is a schematic arrangement of the metallic layers of one form of the condenser.

In accordance with my invention, the rotor and stator elements are composed of a suitable ceramic material having low dielectric losses and 40 a small thermal coefficient of expansion. They can be produced in a well known manner by a casting or pressing process. The ceramic material may preferably consist of a mixture of soapstone, porcelain earth and other additional substances and which is a native material known in the art under the name steatite. Due to the 45 ceramic material being substantially inelastic, or free from elasticity, condensers produced therefrom have the further advantage over those made of metal that practically no oscillations of the component parts at low or audio frequencies, and which may periodically affect the capacity, are developed.

In the embodiment shown, the stator member 55 a consists of a cylindrical wall a₁ the left end

10 of which is open and the opposite end consists of a closed rectangular bottom or base member a₂ having an integral conical extension a₃ which is interiorly ground to form a bearing for a conically enlarged end p of rotor shaft g which 5 may be rotated by a knob or other known means (not shown). As shown in Fig. 3, the stator has an integrally formed projecting boss f at each corner thereof to which may be secured by screws f₁ an elastic metallic plate e which not 10 only reinforces and strengthens the stator but also serves as a supporting means therefor and as an electrical shield to shield the condenser from electrical disturbances in front of the panel. The plate e may be secured to a supporting spider c 15 by any known means such as the screws r which enter tapped holes in the insulating member c, as shown. The spider c as shown has four radially extending arms f₂ each having an aperture 13 through which any suitable securing means 20 such as screws may be passed to secure the entire assemblage to the rear surface of a mounting panel or the like (not shown). The rotor element b consists of a substantially cylindrical portion 13 connected to a central, tapered portion 14 by a 25 radially extending portion 15, the entire rotor element being formed of a single mass of ceramic material. The rotor is shown secured to the conical portion p by means of a nut q screwed onto the threaded end of p, a ring or washer h 30 being interposed therebetween. The condenser plates m₁ and n₁ are formed by spraying finely divided metal onto substantially half or 180 degrees of the outer and inner surfaces of the rotor b and stator a until thin continuous layers are 35 formed.

Or the condenser plates may be formed by galvanizing the metal onto the surface of the rotor and stator elements in a manner known to those skilled in the art of the deposition of metals. 40 If only about 180 degrees of the opposing wall surfaces of rotor and stator are covered or coated with metal, the available surfaces are not fully utilized. To provide a condenser of substantially twice the capacity, two separated layers each of 45 about 170 to 175 degrees extent may be applied to the surfaces of rotor and stator elements as shown in Figs. 3 and 4. It is then necessary that the one layer for instance n₁ of the rotor be continuously conductively connected to one layer, such as m₁, of the stator and also layer n₂ of the rotor should be similarly connected to layer m₂ of the stator. This may be accomplished by metallic brushes K₁ and K₂ supported by the rotor and bearing near their outer ends on metallic 55

- segmental members l_1 and l_2 supported by the stator and connected to the layers m_1 and m_2 the members l_1 , l_2 and m_1 and m_2 having substantially the same angular extent, as shown in Fig. 3a.
- 5 The inner ends of the brushes K_1 and K_2 may be connected to layers n_1 and n_2 by the rivets 16 having heads 17 in contact with the layers. Members l_1 and l_2 may also serve as the terminals for the condenser.
- 10 Having described my invention, what I claim and desire to secure by Letters Patent is:
1. A variable condenser comprising a rectangular shaped member having a hollow cylindrical shaped extension, a spider member having a plurality of extending arms and a central hub portion, a metallic plate secured to said hub portion and to said rectangular shaped member, a metallic coating secured to the inner surface of said extension, a rotor shaft journaled in said hub portion, an elongated member formed of insulation material secured to said rotor shaft and having an exterior cylindrical surface and a me-

tallic coating secured to said last named surface and adapted to lie closely adjacent to and opposite said first named coating at a predetermined angular position of said rotor shaft.

2. A variable condenser comprising in combination, a central stationary member, a thin, flexible metallic plate secured to said member and extending outwardly therefrom, a stator element composed of insulating material and formed into a hollow cylindrical drum, screw means securing 10 said stator element to the outer portion of said plate, a thin layer of metal coated over the inner surface of said drum over an area slightly less than 180 degrees, a rotor element composed of insulating material and mounted within said stator element and having its exterior surface of cylindrical form, a thin layer of metal coated over the exterior surface of said element over an area of slightly less than 180 degrees, a shaft passing 15 through said rotor and stator elements and means 20 securing said rotor element to said shaft.

ARTHUR SCHMIDT.
